Be it known that I, Leandro P. Rizzuto, have invented a new, original, and ornamental design for an electric hair dryer, of which the following is a specification, reference being had to the accompanying drawings, forming a part hereof.

FIG. 1 is a left side perspective view of an electric hair dryer showing my new design;

FIG. 2 is a front elevational view;

FIG. 3 is a left side elevational view;

FIG. 4 is a top plan view;

FIG. 5 is a rear elevational view;

FIG. 6 is a right side elevational view; and

FIG. 7 is a bottom plan view.

In the foregoing views, the cord is shown only partially for convenience of illustration.

I claim:

The ornamental design for an electric hair dryer, substantially as shown and described.
